METAL STRETCHING AND CONTOUR FORMING MACHINE

Cyril J. Bath, Chagrin Falls, Ohio, assignor to
The Cyril Bath Company, Cleveland, Ohio, a
corporation of Ohio

Application February 17, 1944, Serial No. 522,700

18 Claims. (Cl. 153—40)

1

This invention relates to a metal working machine for forming stock pieces such as rods, bars, tubes, pipes, sheets and shapes into regularly or irregularly curved or contoured forms. The subjecting of such a stock piece of metal to a stress approaching, or slightly exceeding, its elastic limit, and conforming it to a master shape or die, has heretofore been accomplished by various types of machines, apparatus, and special tools and jigs. Such machines have usually been designed to accomplish the specific metal shaping design at hand, or for a particular type of stock or blank form.

The general object and nature of my invention is to provide a contour forming machine which is capable of operating equally well upon rods, bars, tubes, pipes, sheets and shapes, and in which a practically unlimited range of contours can be produced.

The forming of metal to a contoured master shape while it is stressed to its elastic limit has in practice been found to be a rather difficult operation, particularly in the case of metals whose elastic limit and ultimate strength are of relatively close values. As a piece of metal stock, such as a bar or angle shape, is placed under a tension which is initially determined to be its elastic limit, and then formed around a contoured shape, it is often quite likely that stresses will be imparted to the metal during the subsequent forming operation which exceed both the elastic limit and the ultimate strength whereupon the material is fractured and the entire workpiece ruined.

It is, accordingly, a further object of my invention to provide a metal tensioning means which is operative to apply the tensioning force at all times tangent to the surface of the forming die. To the accomplishment of this objective, I provide a rotatable die supporting table and a power cylinder and piston for tensioning the workpiece, such cylinder being pivotally mounted upon an axis parallel to that of the table whereby it may pivot or swing, thus permitting the "laid on" workpiece to occupy a tangent position with respect to the forming die, and wherein the direction of application of the tensioning force (through the longitudinal axis of the pressure cylinder) is likewise at all times in alignment with such tangent. The rate at which the tensioned workpiece is laid upon an irregularly curved or contoured die often varies throughout the extent of the forming operation. In order to compensate for this factor, while simultaneously maintaining a uniform tensioning stress, my invention

also provides an automatic pressure control system for maintaining the same tensioning force in the pressure cylinder, regardless of the rate at which its piston might be caused to move inwardly or outwardly during the working cycle.

In certain contour forming operations, I have found it desirable to apply a compressive forming force in addition to the tensioning stress on the workpiece. In other words, while the workpiece which is being stretched to its elastic limit is laid upon the forming die, it is also desirable in certain instances simultaneously to exert a compressive ironing or rolling force against the workpiece, such as, for example, when negotiating corners and curves of relatively small radius, or forms having reverse curvatures.

Additional objects and advantages of my invention shall become apparent as the following description proceeds.

To the accomplishment of the foregoing and related ends, said invention then comprises the features hereinafter fully described and particularly pointed out in the claims, the following description and the annexed drawings setting forth in detail certain illustrative embodiments of the invention, these being indicative, however, of but a few of the various ways in which the principle of the invention may be employed.

In said annexed drawings:

Fig. 1 is a side elevational view of a machine embodying the principle of my invention;

Fig. 2 is a top plan view thereof;

Fig. 3 is a perspective view thereof;

Fig. 4 is a partial perspective view similar to Fig. 3, but showing the machine operating upon sheet stock;

Fig. 5 is a diagram representing a hydraulic pressure control system for the pressure cylinder;

Fig. 6 is a detailed, sectional view of a die table limit stop abutment block;

Fig. 7 is a diagrammatic view illustrating the relative positions of movement of the die table and tensioning cylinder during the contour forming working cycle;

Fig. 8 is a view similar to Fig. 7 but showing the workpiece being formed to a different contour;

Fig. 9 is a top plan view of a modified form of construction for mounting the pressure cylinder and in which the latter is adapted for both tension and compression operation;

Fig. 10 is a partial side elevation of Fig. 9;

Fig. 11 is a sectional view taken upon a plane normal to Fig. 10 and substantially along line 11—11 thereof;

Fig. 12 is a top plan view of another modified form of machine embodying the principle of my invention, such machine being adapted for combined tensioning and compressing operation upon the workpiece;

Fig. 13 is a side elevational view of a portion of Fig. 12; and

Figs. 14 and 15 are diagrammatic views similar to those of Figs. 7 and 8, but illustrating the machine, as set up with a compression holding cylinder on the die table, and having a die of reversed curvature contour.

Now referring more particularly to Figs. 1-3, incl., the machine shown therein comprises a supporting and housing base 1 adjacent whose left-hand end the die supporting table 2 is rotatably mounted. The table 2 is carried upon the vertical shaft 3 which in turn is journaled at the upper and lower bearings 4 and 5, respectively, in the base 1. Thrust bearing plates are provided at 6 for rotatably carrying the weight of the table 2.

A large ring gear 7 is carried on the underside of the table 2, as by the screw bolts 8 and is adapted to be engaged by the small pinion gear 9 which in turn is carried upon the vertical shaft of the one way drive or self-locking worm and gear unit 10. The drive pulley 11 on the unit 10 is connected by means of the belt 12 through the pulley 13 on the variable speed transmission 14, the latter in turn being driven through the electric motor 15.

The hydraulic pressure cylinder 16, carrying the piston rod 17 is fastened at its end plates 18 and 19 to the elongated base plate 20. The plate 20 is in turn secured to the disc plate or table 21 which is rotatably mounted by means of the stub shaft 22 journaled in the circular supporting plate 23. The table 21 has a circumferential shoulder as indicated at 24, which is engaged by the retaining ring 25. The cylinder 16 is thus pivotally mounted, in a direction transverse to its longitudinal axis, upon the flat top wall portion 26 of the base 1.

Referring to Fig. 2, it will be seen that the axes of the table 2, and of the table 21, as represented by the shafts 3 and 22, respectively, and that the axis of the pinion gear 9, are all in alignment with respect to the base 1. Thus, the rotating driving force imparted from the pinion gear 9 to the table 2 is in alignment with the reaction forces transmitted to the shaft 3, as well as being in alignment with the reaction forces transmitted from the cylinder 16 to the shaft 22; all of such forces being received at the longitudinal mid-plane of the base 1 where the maximum strength of the latter is available to withstand them.

The piston rod 17 carries an L-shaped pedestal 27 whose horizontal or bottom leg engages in the dovetail slideway 28 on the base plate 20. As will be seen from Fig. 3, the pedestal 27 is adapted to mount a workpiece clamp 29 in the desired vertical position, being provided with undercut grooves (see Fig. 1) whereby such clamp may be adjustably secured thereto. The other end of the workpiece W is held in the clamp 30 on the end of the forming die 31 which in turn is bolted to the top of the table 2. Said die is laterally facing, i. e., the face thereof with which the workpiece contacts is disposed transversely of lines radial to the axis of the table.

In Fig. 4, the machine is shown as set up for operating upon a workpiece W_a which is a relatively wide piece of sheet stock. In this case, the vertical leg of the pedestal 27 is utilized to give firm support to the relatively long clamp 29a.

A relatively high or wide die 31a, together with the clamp 30a, which grips the other end of the workpiece, forms the latter as the table 2 is rotated and tension is applied by the hydraulic cylinder 16. It will be seen that the slideway 28 cooperates with the bottom leg of the L-shaped pedestal 27 to maintain the vertical leg portion thereof in proper alignment during the movement of the piston rod 17, particularly when operating upon sheet stock, such as the workpiece W_a. This in turn counteracts any tendency of the clamp 29a to become cocked or misaligned during the contour forming operation and coincidentally, prevents the setting up of unequal stresses and strains in the workpiece.

An electric drive motor 32, contained within the housing 1, drives the hydraulic pump 33, which is connected to the cylinder 16 by means of the hydraulic system diagrammatically illustrated in Fig. 5. The pump 33 delivers pressure to the pressure regulating valve 34 which in turn is connected to the line 35 to the distributing valve 36. The pressure regulating valve 34 is of the adjustable type, as well known to those skilled in the art, so that its delivery output pressure may be set at a predetermined value, indicated upon the pressure gauge 37. The distributing valve 36 is operated by means of a lever 38, suitably accessible on the exterior of the base housing 1 and is adapted alternatively to connect the pressure line 35 to the lines 39 and 40 leading to the rod and head end respectively of the cylinder 16.

The exhaust outlet of the pressure regulating valve is connected through the line 41 to the flow control valve 42 which in turn is connected to the exhaust line 43 leading back to the pump reservoir 44.

The actuation of the drive motor 15 is controlled by an operating lever 45. A limit switch 46 is connected in series with the motor switch actuated by the lever 45 and has an operating lever 47 extending into the peripheral groove 48 on the side of the table 2. Adjustably locatable limit stop abutment blocks 49 are adapted to be engaged in the groove 48. As seen from Fig. 6, the abutment blocks 49 are composed of the two wedge-shaped halves 50 and 51 which are drawn together by the cap screw 52 and thus caused to grip the top and bottom walls of the groove 48.

The operation of the apparatus as hereinabove described is as follows:

The workpiece is gripped between the clamps 29 and 30, Fig. 3. The table 2, with the forming die block, such as the one indicated at 31 attached to its upper surface, is at first in a position substantially 90° clockwise removed from that shown in Fig. 3, and wherein the workpiece is still in its straight line form. The lever 38 is then operated to introduce pressure to the cylinder 16 and to place the workpiece W under a tension equal to its elastic limit, as indicated on the pressure gauge 37, and as determined by the regulation of the pressure regulating valve 34. The lever 45 is then operated to start the drive motor 15 and correspondingly the table 2, to rotate in a counter-clockwise direction whereupon the workpiece is "laid on" or wrapped around the forming surface of the die 31.

As previously described, the driving connections between motor 15 and the table are of one-way or self-locking type, so that rotation of said table will be restrained or braked against slippage under pull of the workpiece when the latter is placed under tension in the manner just set forth. In other words, rotation of the table at certain stages

of operation is permitted or controlled, rather than produced, by the motor.

At any point in this operation where the tension on the workpiece W and hence the pressure in the rod end of the cylinder 16 exceeds the predetermined setting of the pressure regulating valve 34, pressure introduced to the latter from the pump 33 will be by-passed or flowed off through the flow control valve 42. The valve 42 insures against any sudden pressure drops or reverse surges which might tend to occur in the system upon the sudden by-passing of the pump pressure. In the event that the piston 17 should have to move in the opposite direction (viz. inwardly of the cylinder 16), which might be caused by the particular configuration of the die, the slightest drop in pressure in the cylinder 16 would immediately operate to connect the valve 34 to the line 35, so that the predetermined pressure would be maintained in the cylinder 16 in such direction of travel. Thus, the correct tensioning force is exerted by the piston 17 at all times during the forming operation, viz., rotation of the table 2, and regardless of its relative in or out movement.

As the table 2 rotates to the point where the workpiece W is completely laid on or formed around the die 31, the limit stop block 49 contacts the finger 47 of the switch 46, stopping the motor 15 and the rotation of the table 2. As the lever 45 is moved to reverse position to drive the motor 15 and the table 2 in opposite direction, the other limit stop block 49' (see Fig. 2) operates to stop the table 2 at the proper position for receiving another workpiece and repeating the forming operation.

It will be noted that as a result of attaching the one end of the workpiece to the pedestal or slide 27 instead of directly to the end of the piston rod 17, the latter is relieved of all side strain due to changing angularity in the direction of the pull on the workpiece. In other words, inasmuch as said slide is supported in the slideway 28, which is of substantial construction, the strains in question will be taken up by the latter so that the piston and its actuating cylinder need only maintain the necessary longitudinal pull on the workpiece. The operation of such piston and cylinder is accordingly much facilitated and wear thereon greatly reduced.

Figs. 7 and 8 diagrammatically illustrate the operating positions of the machine for different types of contour forming work. In Fig. 7 the machine is represented as operating upon a die form of substantially uniform curvature. The starting position of both the table 2 and cylinder 16 is indicated in full lines at A, the half-way position at B, and the finishing position at C, the latter two positions being shown in dotted lines. It will thus be seen that the workpiece W in Fig. 7 is laid on to the forming die in tangent relationship to the contoured surface of the latter, and that the cylinder 16 takes up pivotal positions permitting the maintenance of this tangent relationship. It will be seen that the total amount of movement of the piston 17 is relatively small for the length of the workpiece W. In the case of Fig. 7, this movement is unidirectional and substantially uniform from start to finish.

In Fig. 8, the die form is of an irregular degree of curvature. It will be noted that the piston 17 in this instance first moves inwardly from the starting position A to the intermediate position B and finally reverses its movement and moves slightly outwardly to the final position C. Re-

ardless of this irregular and reversed movement of the piston 17, the tension exerted upon the workpiece W nevertheless remains uniform and constant throughout the forming operation, due to the operation of the hydraulic control system hereinabove described.

In the modified form of the machine as shown in Figs. 9-11 incl., the hydraulic cylinder 60 with its piston is so mounted on the base frame 1' as to be adjustable to various positions with respect to the axis of the die table 2, while being capable of swinging on its pivotal mounting when its piston is reciprocated for tensioning action, or of being fixedly mounted when its piston is reciprocated for compressive action. The cylinder 60 has its end plates 61 and 62 bolted to the base plate 63 which is in turn pivotally mounted to the block nut 64 by means of the stub shaft 65. The nut 64 is held against rotation and adapted to slide along the angle bars 66 and 67 secured to the underside of the top wall of the base 1'.

A rotatable feed screw 68 engages with the nut 64. An elongated slot or opening 69 is provided in the top wall of the base 1' to permit the back and forth movement of the nut 64 and of the connecting shaft 65.

The feed screw 68 is journaled at each end in the bearing bosses 70 and 71 and is rotated by suitable means such as by the drive motor 72 connected to the pulley 73 mounted on the end of the feed screw 68.

The end of the base plate 63 supporting the cylinder 60, opposite to its pivotal mounting at the shaft 65, is supported upon the rollers 74 and 75. As will best be seen from Fig. 9, the axes of these rollers are so disposed as to permit the rollers to travel upon the circumference of a circle whose center is the center of the shaft 65.

The cylinder 60 has a piston rod 76 connected to the mounting pedestal 77 which, like the previously described pedestal 27, has a bottom horizontal leg engaging in the dovetail slideway in the plate 63.

It will thus be seen, that by adjusting the position of the plate 63 and the cylinder 60 on the top of the base 1', that a wide range of forming die sizes on the table 2 can be accommodated, so that it can be moved up to position where the pedestal 77 overhangs the circumference of the table 2 (as shown by dotted lines in Fig. 9) for working on relatively small dies or for compression work; or it may be moved a substantial distance away from the table 2 for larger dies and for certain long stretching operations. When the cylinder 60 is moved closest to the table 2, or in the position shown in dotted lines in Fig. 9 and employed for compression or rolling operations, it is locked against pivotal movement by means of locking bolts 79 and 80 fitting through holes in the bosses 81 and 82, respectively, and through the top wall of the base 1'.

As shown in Fig. 9, when the cylinder 60 is thus locked against the pivotal movement and employed for compression rolling operation, the pedestal 77 carries a suitable work contacting tool such as the double rollers 83 and 84 adapted to contact against the side of the workpiece W being wrapped around the die 85. The rollers 83 and 84 are mounted in the carriage 86 which is pivotally attached as indicated at 87 to the pedestal 77.

In the form of construction in Figs. 12 and 13, the machine shown therein is adapted to perform combined tensioning and compression rolling op-

erations on the same piece of stock. As will be seen from Fig. 12, the base of the machine is substantially L-shaped, comprising the legs $1a$ and $1b$ emanating radially, and in angularly spaced relationship (specifically at an angle of 90° as shown in Fig. 12) from the center of the die table 2 . The base portion $1a$ supports the pressure cylinder 69 , forming rolls 83 and 84 , of the same construction as last described in connection with Figs. 9-11. The base portion $1b$ supports the tension cylinder 90 which is adapted to grip the workpiece W at the clamp 91 on the end of its piston rod 92 . The rod end casting 93 of the cylinder 90 is mounted in the slideway 94 of the vertical column 95 . A feed screw 96 , operated by means of the hand crank 97 , engages with the cylinder end casting 93 for moving the cylinder 90 to desired vertical positions.

The vertical column 95 is mounted on a table 98 which in turn is pivotally supported within the sliding carriage 99 as shown in dotted lines in Fig. 12. The carriage 99 rides upon the slideways 100 and 101 on the top of the base portion 16. A pinion 102, journaled in the downwardly projecting leg 103 from the carriage 99, engages with the gear rack 104, and is adapted to be operated by the crank 105.

Stop blocks 106 are provided at intervals across the top of the base portion 1b and are adapted to be engaged by the locking dog 107 which fits between such stop blocks and the right-hand front face of the slide carriage 99.

Thus, by operating the pinion 102, the carriage 99 together with the cylinder 90 may be moved to a plurality of desired positions on the top of the base portion 1b, and there locked against longitudinal movement by the dog 107. A wide range of workpiece links can thus be accommodated. In the operation shown in Fig. 12, the cylinder 90 is shown exerting a tension stress upon the relatively long workpiece W whose end is being formed in a compound curvature shape on the die 108, and simultaneously compressed or rolled against such die by the compressive force exerted by the cylinder 60.

In Figs. 14 and 15, the principle of my invention is shown as being applied to the contour forming of reverse bends in the stock. Thus, the die 131 will be seen to comprise the convex portion 132 merged with the concave portion 133 which in turn joins with the second convex portion 134 of the die forming surface. In Fig. 14 the workpiece W is shown being formed over the convex die surface portion 132, in the same manner as previously described herein. However, when the die table 2 turns further in a counter-clockwise direction with respect to Fig. 14, the workpiece W would normally bridge over the reverse bend or concave die portion 133. Hence, the hydraulic cylinder 135 with its piston 136 is mounted opposite the die portion 133, viz., on a line normal to the major chord of the curvature of the portion 133. A male die or pad 137 is carried on the end of the piston rod 136, and when the die table 2 reaches a position where the workpiece W tends to contact the high points of both the portions 132 and 134, the cylinder 135 is operated to press the workpiece W into the reversed bend portion 133, substantially as shown in Fig. 15. The pad 137 is held in such position as the die table 2 continues to rotate and thus form the remainder of the workpiece contour around the convex die portion 134.

Other modes of applying the principle of the invention may be employed, change being made as regards the details described, provided the fea-

tures stated in any of the following claims or the equivalent of such be employed.

I therefore particularly point out and distinctly claim as my invention:

- 5 1. In a contour forming machine a base, a rotatable table thereon, means to rotate the table, a pair of metal forming piston and cylinder assemblies, connecting means respective to and connecting the assemblies with their axes generally parallel to a plane normal to the axis of the table and extending generally toward and away from the table, one assembly on the base and the other for rotation with the table, the table being adapted to support a side face die
10 means for supplying pressure fluid to said one assembly so as to yieldably urge its piston in a direction generally away from the table, means for supplying pressure fluid to the other assembly so as to yieldably urge its piston in a predetermined direction and means on the piston of said one assembly adapted to be connected to the end of a workpiece when the workpiece is in contact with the side face of the die so as to exert tension on said workpiece.
15 2. The structure according to claim 1 characterized in that the connecting means of said one assembly includes a pivot generally parallel to the table axis and which pivot connects said one assembly and base so that the said one assembly is swingable about the axis of the pivot.
20 3. The structure according to claim 2 characterized in that the connecting means of said other assembly constrains said other assembly from swinging movement relative to the table.
25 4. In a contour forming machine a base, a rotatable table thereon, means to rotate the table, a pair of metal forming piston and cylinder assemblies, connecting means respective to and connecting the assemblies on the base in angularly spaced relation to each other about the table axis and with their pistons extending generally toward and away from the table and their axes generally parallel to a plane normal to the table axis, means for supplying fluid under pressure to one assembly so as to yieldably urge its piston in a direction generally away from the table, means for supplying fluid under pressure to the other assembly so as to yieldably urge its piston in a direction generally toward the table said table being adapted to support a side face die for rotation therewith, means on the one of the pistons urged generally away from the table adapted to be connected to the end of a workpiece, when the workpiece is in contact with the side face of the die, so as to exert tension on the workpiece, and the piston of the other assembly being adapted for connection to a workpiece engaging tool.
30 5. The structure according to claim 4 characterized in that the connecting means of said one assembly includes a pivot parallel to the table axis and which pivot connects said one assembly and base so that said one assembly is swingable about the axis of the pivot.
35 6. In a contour forming machine a base, a rotatable table thereon, a side face die supported on the table, means to rotate the table, a pair of metal forming piston and cylinder assemblies, connecting means respective to and connecting the assemblies with their axes generally parallel to a plane normal to the axis of the table, one assembly on the base and the other assembly on the table for rotation therewith, said assemblies being positioned so that the pistons are

movable relatively toward and away from the side face of the die, the piston of one of said assemblages being adapted to exert tension on the end of a workpiece contacting the side face of said die and the piston of the other of said assemblages being adapted to exert metal forming force on the workpiece in a direction generally toward the side face of the die.

7. The structure according to claim 6 characterized in that the connecting means of said one assemblage includes a pivot parallel to the table axis and which pivot connects said one assemblage and base so that the said one assemblage is swingable about the axis of the pivot.

8. The structure according to claim 7 characterized in that the connecting means of said other assemblage constrains said other assemblage from swinging movement relative to the table.

9. In a contour forming machine a base, a rotatable table thereon, a side face die mounted on said table, means to rotate the table, a pair of metal forming piston and cylinder assemblages, connecting means respective to and connecting the assemblages on the base in angularly spaced relation to each other about the table axis and with their pistons extending generally toward and away from the table and their axes generally parallel to a plane normal to the table's axis, the piston of one assemblage being adapted for connection to the end of a workpiece contacting the face of the die so as to exert force in a direction away from the die for tensioning said workpiece contacting said die face, and the piston of the other assemblage being adapted to exert force on the workpiece in a direction generally toward the side face of the die.

10. The structure according to claim 9 characterized in that the connecting means of said one assemblage includes a pivot parallel to the table axis and which pivot connects said one assemblage and base so that the said one assemblage is swingable about the axis of the pivot.

11. In a contour forming machine a base, a rotatable table thereon adapted to support a side face die, a metal forming piston and cylinder assemblage mounted on the base with its axis in a plane generally normal to the table axis and with its axis extending generally toward and away from the table for transverse swinging movement about an axis generally parallel to the table axis, a guide mounted in fixed position relative to the assemblage and swingable therewith about the swinging axis of the assemblage and extending parallel to the longitudinal axis thereof, a tool holder reciprocable in the guide and connected to the piston, means to rotate the table, and means to supply pressure fluid to the cylinder so as to yieldably urge the piston in a direction generally away from the table.

12. In a contour forming machine a base, a rotatable table thereon, means to rotate the table, a side face die on the table, a piston and cylinder assemblage supported on the base with its longitudinal axis in a plane generally normal to the axis of the table, and with its axis extending generally toward and away from the face of the die, clamping means secured for rotation with the table and connected for movement with the piston, respectively, for engaging the opposite ends of a workpiece, means for supplying pressure fluid to said assemblage so as to urge the piston in a direction generally away from the die with force to apply sufficient tension on the workpiece to cause the workpiece to conform substantially to the side face of the die upon release of

the workpiece after the table has been rotated with said tension applied.

13. The structure according to claim 12 characterized in that said assemblage is connected to the base for swinging movement about an axis generally parallel to the axis of the table and through an arc such that the workpiece held under tension by the piston and lying between the piston and instantaneous line of contact between the workpiece and the side face of the die during rotation of the table is tangent to the side face of the die at said line of contact.

14. A combined stretching and bending machine for bending elongated members into predetermined shapes, comprising a base, a turntable rotatably mounted thereon, a side face bending die, means for detachably mounting the die on the turntable, means adapted to anchor the front end of one of said members in fixed position relative to the die, means for rotating the turntable to wrap said member around the die while the rear end of the member is thereby drawn forward toward the die, a piston adapted to be connected to the rear end of the member, a fluid pressure cylinder housing the piston, and means pivotally mounting the cylinder on said base on an axis parallel to and a fixed distance from the axis of the turntable, said cylinder being adapted to receive fluid pressure in front of the piston whereby to resist forward movement of the piston in the cylinder so as to exert sufficient tension on the member so that when it is wrapped around the die by rotation of the table against the tension exerted by the piston and released it will substantially conform to the shape of the die.

15. A combined stretching and bending machine for bending elongated members into predetermined shapes, comprising a base, a turntable rotatably mounted thereon, a side face bending die, means for detachably mounting the die on the turntable, means adapted to anchor the front end of one of said members for rotation with the turntable, means for rotating the turntable to wrap said member around the die while the rear end of said member is thereby drawn forward toward the die, a piston adapted to be connected to the rear end of said member, a fluid pressure cylinder housing said piston, and means pivotally mounting the cylinder on said base on an axis parallel to and offset from the axis of the turntable, for swinging movement about said pivotal axis through the maximum arc subtended by the path of the die, said cylinder being adapted to receive hydraulic fluid pressure in front of the piston whereby to resist forward movement of the piston in the cylinder sufficiently to stretch said member near to its elastic limit.

16. In a contour forming machine, a base, a rotatable table thereon adapted to support, for rotation therewith, a side face die about which a length of metal can be wrapped and a stock anchor for securing a portion of the length of the metal for rotation with the table, a pair of metal stressing fluid pressure operated piston and cylinder assemblages, means respective to the assemblages and connecting them, one to the base and one to the table for rotation with the table, with their axes generally parallel to a plane normal to the table axis, means for supplying fluid pressure to one of said assemblages for urging its piston generally away from the table, means for supplying fluid pressure to the other of said assemblages for urging its piston in a direction generally toward the table, means carried by the 75 piston of said one assemblage and adapted for

11

connection to a length of metal for exerting tension thereon upon said movement of the associated piston generally away from the table, and a metal engaging tool carried by the piston of said other assemblage for applying pressure to the length of metal in a direction generally toward the table.

17. In a contour forming machine, a base, a rotatable table thereon, means to rotate the table, a pair of metal stressing piston and cylinder assemblies, connecting means respective to and connecting the assemblies on the base in angularly spaced relation to each other about the table axis and with their axes generally parallel to a plane normal to the table axis and connecting one of them to the base for swinging movement about an axis generally parallel to and offset from the table axis, means for supplying fluid under pressure to the assemblies, respectively, so as to yieldably urge the piston of said one assembly generally away from the table and the piston of the other assembly in a predetermined direction, respectively, means on the piston of said one assembly adapted for connection to a workpiece so as to exert tension thereon, and the piston of the other assembly being adapted for connection to a workpiece engaging tool.

18. A combined stretching and bending machine for bending elongated members into predetermined shapes, comprising a base, a turntable 30 rotatably mounted thereon and adapted to support, for rotation therewith, a bending die and a stock anchor for anchoring one end of one of said members for rotation with the die, means for rotating the turntable, whereby said members, 35 when so anchored, can be wrapped around the die while the rear end of said member is thereby drawn forward toward the die, a piston adapted for connection to a clamp to be connected to the

12

rear end of said member, a fluid pressure cylinder housing said piston and having its axis generally parallel to the plane of the table, means pivotally mounting the cylinder on said table on an axis parallel to and offset from the axis of the turntable, said cylinder being adapted to receive pressure fluid in front of the piston whereby to resist forward movement of the piston in the cylinder sufficiently to stretch said member near to its elastic limit, pump means for supplying said pressure fluid and connected in a fluid pressure circuit with the piston, constant pressure control means in said circuit and operative to maintain the pressure of the fluid in said cylinder substantially constant during movement of the piston.
